METHOD OF PRODUCING GEARS

Ernest Wildhaber, Brighton, N. Y., assignor to
 Gleason Works, Rochester, N. Y., a corporation
 of New York

Application May 24, 1941, Serial No. 395,072

36 Claims. (Cl. 90—5)

The present invention relates to the cutting of gears and particularly to the cutting of longitudinally curved tooth bevel and hypoid gears.

One object of the invention is to provide an improved method for cutting gears for transmitting non-uniform motion and particularly gears of the varying-leverage type disclosed in my pending application, Serial No. 386,629, filed April 3, 1941, now Patent No. 2,308,558, issued January 19, 1943.

A further object of the invention is to provide a method for cutting gears with teeth of tapering depth for transmitting either uniform or non-uniform motion by which gears may be cut with a face-mill gear cutter that are mathematically correct and which will mesh without "bias bearing."

A further object of the invention is to provide a method for generating non-uniform motion gears in which the same modification of generating roll may be employed in the generation of both sides of the gear teeth.

Another object of the invention is to provide a method for cutting gears in which a gear may be roughed out and one side finish-cut in a single operation and with a single cutter.

Still another object of the invention is to provide a method for cutting gears with which the gears may be completely finish-cut from the solid in one operation and with a single cutter.

A further object of the invention is to provide a method for cutting gears which will permit of employing a cutter having a very large number of cutting blades so as to obtain either tooth surfaces of finer finish or a higher speed of production.

Another object of the invention is to provide a method for cutting gears in which not only the tooth profiles may be finished but the tops of the teeth rounded in a single operation and with a single cutter.

Still a further object of the invention is to provide a method for rough and finish cutting gears in a single operation and with a single tool in which the roughing is effected by certain cutting edges of the tool which do no finish-cutting and the finishing is effected by other cutting edges of the tool which do no rough-cutting but which are saved for the finish-cutting only.

Other objects of the invention will be apparent hereinafter from the specification and from the recital of the appended claims.

In cutting gears according to the present invention, tools having cutting portions or points of zero pressure angle are used, and the tooth

profiles of the gear are produced by imparting a cutting motion to the tool while effecting relative movement between the tool and the gear blank in such fashion that a tangent to the zero pressure angle cutting portion of the tool remains tangent to the tooth profile of the blank in all positions of contact between the tool and blank.

Varying-leverage gears, such as disclosed in my Patent No. 2,308,558, have tooth profiles which are concave for a portion of the height of a tooth and which are convex for the rest of the tooth height. These gears are capable of producing a greater variation in leverage during operation than any such gears heretofore proposed. To cut such gears according to the process of the present invention a tool is used whose side-cutting edge has a convex portion that contains a point of zero pressure angle. The tooth profile is produced by imparting a cutting motion to the tool while effecting a relative rolling movement between the tool and gear blank and simultaneously producing a relative depthwise feed movement between the tool and blank in such timed relation to the rolling movement that the point of zero pressure angle in the cutting edge of the tool describes the desired concave-convex profile on the tooth. Both the ratio of rolling movement and the rate of feed are varied during cutting. Moreover, during the production of a given tooth surface, the feed movement is not continuous in one direction, but has two peaks. The tool is first fed outwardly and then inwardly during generation of the described tooth profile. Part of the tooth profile is produced on the forward roll and the remainder on the return roll.

For other forms of non-uniform motion gears, such as varying-leverage gears having wholly convex tooth profiles, cutting may be effected during roll in one direction only. Here again, however, a tool of zero pressure angle is employed, and cutting is effected by producing a relative roll between the tool and gear blank while effecting a relative feed movement between tool and blank in time with the rolling movement.

For cutting gears that are intended to transmit uniform motion, the timed depthwise feed may be omitted. An involute tooth profile may be produced simply by rolling a tool of zero pressure angle and a gear blank relative to one another in such way that the point of contact between the tool and blank always remains in a plane tangent to the base circle of the blank. The tops of the teeth of such gears may be rounded off, if desired, however, by effecting a slight variation of the ratio of roll at the extreme ends of the roll.

The invention may be applied to the cutting of both spur and tapered gears. In cutting tapered gears, the teeth and tooth spaces are preferably cut to taper in depth from end to end. Gears of tapering tooth depth can be produced by the process of the present invention without "bias bearing," that is, without a tooth bearing or contact which extends diagonally of the teeth. For uniform motion gears, for instance, the points of contact between the tooth surfaces of mating gears remain in the same plane as the points of contact between the tool, which cuts either gear, and that gear during the generation of that gear.

In the cutting of tapered gears, the depthwise feed movement may be a swinging movement about the apex of the gear being cut. Such a motion has special advantage in the cutting of non-uniform motion tapered gears, for, when a swinging feed is used, the variation in ratio of roll required for generation of the tooth profiles will be the same for opposite sides of the teeth. Hence, the same control cam can be employed during generation of one side of the teeth of a gear as during generation of the opposite side of the teeth.

The process of the present invention may be used for finish-cutting only, or for both roughing and finishing. The tip and one side of the tool may be employed for roughing a tooth space during part of the generating roll and the opposite side of the tool may be used for finishing one side of the tooth space during the rest of the generating roll. In this case, the opposite side of the tooth space may be finished with a separate tool in a separate operation. In some instances, however, it is possible to rough and finish-cut both sides of a tooth space in a single operation. Here the tooth space is roughed out and one side finish-cut during part of the roll. Then the tool is set over relative to the work and the opposite side of the tooth space is finished during the rest of the roll. The cutting operation is effected in such a way that the roughing portion of the tool does roughing only and the finishing portion does no roughing but it is saved for finishing only.

Since the finish cutting is done with only a point of the tool or with a small portion of zero pressure angle, the tool need not be of great height. Hence, if a face-mill gear cutter is used as the finishing tool, the cutter may have blades of relatively short height, and consequently a great number of cutting blades may be provided in the cutter. Thus it is possible to obtain a very fine tooth surface finish, or to increase the speed of production.

Figs. 14 to 17 inclusive are fragmentary sectional views, illustrating the construction of other modified forms of face-mill gear cutters, having both inside and outside blades.

As already stated, Fig. 1 illustrates how a varying-leverage gear of concave-convex tooth profile may be produced by the process of the present invention. A tooth of the gear is shown at 20, and 21 designates the gear axis. The tooth has profiles 22 which are concave in their lower or flank portions and which are convex in their upper or face portions.

For cutting such gears, a tool 25 is used which has a convex profile portion 26. This tool may be a reciprocatory tool or it may be a face-mill gear cutter. In the case of a face-mill gear cutter, corresponding side-cutting blades will have convex profile portions such as shown at 26. The convex portion 26 is so formed that there is a point 27 on this portion which is of zero pressure angle or inclination. For a face-mill gear cutter, the tangent 28 to the profile 26 at the point 27 will be parallel to the cutter axis.

To generate a tooth profile 22, the tool and gear blank are made to perform such a motion that the tangent 28 to the cutting edge 26 remains tangent to the tooth profile 22 being cut in all positions of contact between the cutting edge 26 and the profile 22 with the result that the point 27 gradually describes the profile 22. In Fig. 1, a tooth profile 22 is shown in several different positions of rotation about the gear axis 21 during generation of the tooth profile 22. These positions are equally spaced angularly from one another about the axis 21 and are denoted at 22₁, 22₂, 22₃, 22₄, and 22₅, respectively. To produce the tooth profile 22, the tool 25 is so moved relative to the gear blank that when the various points A, B, C, D, E, and F in the tooth profile are being cut, the tangents to the tooth profile 22 at these points will also be tangent to the cutting edge of the tool at the point 27, that is, will be parallel to the tangent 28. The tool thus describes relative to the gear a path such as shown in dotted lines at 30. This path is composed of a lateral component perpendicular to the tangent 28, which is the roll component, and an in-and-out depthwise feed movement in the direction of the tangent 28. The rolling movement must be performed with the same high degree of accuracy as is commonly employed in the

generation of gear teeth, but slight variation in the in-and-out feed movement is permissible since a slight error in position in the direction of the profile tangent 28 will have no measurable influence on the tooth profile shape produced.

To determine the path of generation required to produce a given tooth profile, normals are first drawn to the tooth profile at a series of points. Any such point is then turned about the gear center 21 through such an angle that in the final position the said normal extends in the direction of roll and the profile tangent is parallel to the tangent 28. In other words, a point in the tooth profile is turned through an angle equal to the inclination of its normal to the direction of roll. In this manner, the position of generation, and corresponding tool and work positions can readily be determined. Corresponding positions can, of course, be arrived at by computation based on the above procedure.

In Fig. 1, the various successive positions of the tool required for generation of the points A, B, C, D, E, and F of the tooth profile are denoted at 25₁, 25₂, 25₃, 25₄, 25₅, 25₆, respectively. As will be seen from this figure, when a tooth profile such as shown at 22 is being generated, the displacements of the tool during the generating roll vary for equal angular movements of the work. Thus the lateral displacement between tool positions 25₁ and 25₂ is smaller than between tool positions 25₃ and 25₄. In other words, the ratio of movements of tool and work during generation varies.

The depthwise feed movement also varies. Moreover, it has two peaks which occur at the points of generation of the ends of the tooth profile 22. It is further to be noted that the tool is fed further in when the outer end or point of the tooth profile is being generated at A than when the middle of the tooth profile is being produced at the point E. To produce a convex-concave tooth profile such as shown at 22, the roll is reversed when the point E at the juncture of the convex and concave portions of the tooth profile has been cut, but the tool continues to feed further in to cut the rest of the tooth profile. In this reversal of roll, the direction of the roll movement of the tool as well as the direction of rotation of the work are reversed. The infeed movement continues, however, and is not reversed. It is only reversed after the lowest point in the tooth profile has been cut, which is a position, as indicated clearly on the dotted line 38, that is slightly beyond the point F. The tool is then withdrawn from engagement with the gear blank, and remains in withdrawn position while the blank is being indexed. The tool is then fed back into engagement with the blank to cut a new profile of the blank.

It will be noted that when the tool is cutting at the point F, it is cutting with the blank in the same angular position 22₄ as when the tool is cutting at the point D. The blank, however, is rotating in the reverse direction when cutting is taking place at the point F from the direction in which it is rotating when cutting is taking place at the point D.

The cycle illustrated in Fig. 1 is a finishing cut, and for convenience in illustration it has been assumed that an infinitesimal finishing cut is being made in order to show how the profile is described. Fig. 1 shows the generation of one side of a tooth only. It will be understood, however, that the opposite side of the tooth may be generated by the same method as illustrated in Fig. 1

with a tool suitable for cutting the said side of the tooth.

A gear of the type shown in Fig. 1 may first be roughed out in a forming or other suitable roughing operation and then finish-cut, one side at a time, by the method of the present invention. It is possible, however, to rough out and finish one side in a single operation by the process of the present invention, and then to finish the other side. This method will be described later in further detail in connection with the description of the cutting by the present invention of other types of gears.

When the cutting operation is effected in the manner above described with the tool 25 describing the tooth profile from the tip inwardly, the tool will cut only with its tip 31 and that part of its convex side edge up to the point 21, but not beyond that point. The side-cutting edge of the tool, as a consequence, need not extend much above the point 27. On a face-mill gear cutter, therefore, the gashes between successive cutting blades can be made comparatively shallow with a bottom at 32, for instance. Hence, the height of the blades, viz., the distance between the lines 31 and 32, may be made smaller than the height of the gear teeth to be cut. This makes it possible to provide the cutter with cutting blades that are closer together than in an ordinary face-mill gear cutter. Hence, the cutter may be provided with more cutting teeth than an ordinary face-mill gear cutter so that a better tooth surface finish can be achieved, or more rapid production attained.

Fig. 2 illustrates how the process of the present invention may be applied to the production of another type of varying-leverage gear where the tooth profile consists of a single convex circular arc for most of its height with a sharply rounded convex portion at the top of the profile. Here the tooth profile can be fully described during rolling motion in one direction, and it is not necessary to cut on both the forward and return rolls in order to generate the complete tooth profile. 40 denotes a tooth of the gear which is to be cut. 41 is the axis of the gear, and 42 one of the tooth profiles. The tool 45 used for finish cutting the profile 42 has a straight side 46 of zero pressure angle and finishes the profile 42 with a point 47 of that profile. Here again, the generating motion comprises a lateral feed or roll in a direction perpendicular to the straight side 46 of the tool and an in-and-out depthwise feed motion in the direction of said side 46.

The tool may be a reciprocating tool or it may be a face-mill gear cutter whose axis is parallel to the side edge 46. In the latter case, the finishing surface of the tool comprises the cutting edges of all the corresponding blades of the cutter and 60 is a cylindrical surface.

42₁, 42₂, 42₃, 42₄, and 42₅ denote successive positions of the tooth profile in the generating operation. These positions are spaced equi-angularly from one another about the axis 41. In the production of the tooth profile, the tool moves at a varying velocity relative to the work. Successive positions of the tool for the shown angular positions of the tooth profile are denoted at 45₁, 45₂, 45₃, 45₄, and 45₅, respectively. The path of the point of contact between the tools and the tooth profile during generation is denoted at 48. When the tooth profile 42 has been completely described, the tool is withdrawn from engagement with the work, the roll is reversed to return the tool to initial position, the blank

is indexed, and the tool is fed back into engagement with the blank ready to describe another tooth profile of the blank. The dotted line 49 denotes the path of the tool during withdrawal; the dotted line 50, the path of movement of the tool after it has been withdrawn and while indexing is taking place; and the dotted line 51 the path of movement of the tool while it is being fed back into engagement with the blank ready for the cutting of the next tooth profile.

In cutting cylindrical gears with a face-mill gear cutter that has an effective cutting portion of cylindrical form, the individual depthwise positions of the tool are unimportant. Thus, it will be seen that the same tooth shape would be produced whether the tool is in the shown position 45₃ for the position 42₃ of the tooth profile or whether the tool is at some other position further in in the direction of tooth depth. This situation does not prevail, however, in the case of bevel gears where the in-and-out feed is a swinging feed about the apex of the gear. There the feed movement should be such as to insure that the tool attains the disclosed positions for the disclosed positions of the work, although even here some tolerance in the depthwise position of the tool for the different points of roll is permissible.

Use of the swinging feed about the gear apex in the generation of bevel gears according to the present invention has the advantage that the motions employed are symmetrical for opposite sides of the teeth. The tooth profiles produced are also symmetrical, and the same roll modification can be used for all cone distances and cutter diameters.

Heretofore, it has been required to use face-mill gear cutters of spherical form in order to produce varying-leverage bevel gears of tapered depth without "bias bearing." Mathematically correct varying-leverage level gears may be produced, however, by the method of the present invention and such gears will mesh without "bias bearing." Lengthwise localization of tooth bearing may be obtained, as usual, by providing face-mill gear cutters for cutting the two members of the pair which will cut longitudinally concave tooth surfaces on each member of the pair that have a radius of lengthwise curvature larger than the radius of lengthwise curvature of the mating longitudinally convex tooth surfaces of the other member of the pair.

Fig. 3 illustrates a method of cutting uniform motion bevel gears by the present invention with a face-mill gear cutter and in such manner as to avoid "bias bearing." This method may be employed for roughing the tooth slots and finishing one side from the solid in a single operation. Here the pinion or gear to be cut is denoted at 60. It has teeth 61 whose tooth profiles 62 and 63 are involutes having a base circle denoted at 64. Tangent 65 to the base circle 64 is perpendicular to an involute tooth profile of the gear at the points of intersection of that profile with the tangent, as is well known. The tooth profiles 63 of the gear may, therefore, be formed with a face-mill gear cutter 68 that has a straight finish-cutting portion 69 that is parallel to the axis 70 of the cutter and perpendicular to the tangent 65. The cutter is so positioned relative to the gear that a plane containing the tangent 65 and perpendicular to the cutter axis 70 also contains the apex of the bevel gear. The tip surface 72 of the cutter extends inwardly at a constant distance below this plane and cuts a root surface 73 in a tooth space of the gear which is parallel to the base cone 64. 75

of the gear. The root surface produced on the gear has, therefore, the same cone angle as the base cone but a different cone apex.

As in the previously described embodiments of the invention, the tooth profile 63 is finished by a single point 74 in the cutting edge 69 of the tool. The profile 63 is generated by rotating the blank 60 on its axis at a uniform velocity while moving the tool 68 at a uniform velocity in the direction of the tangent 65. The finished tooth shape is generated by the point 74 in the cutting edge of the tool as the point 74 travels along the tangent line 65. 68₁ denotes one extreme position of the tool during generation of the tooth profile 63, and 68₂ denotes another position in the generation of such profile. In the latter position, contact between the tool and the tooth profile takes place at the highest point in the tooth profile. The position of the tooth profile during generation of this point is denoted at 63'. The dotted line 75 denotes the path of travel of the point 74 of the cutting edge of the tool during withdrawal, while withdrawn, and during return to operative position.

25 The blade 68 may have a straight side-cutting edge 69 for a portion of its height only. The rest of the height of the cutting edge may be made concave as denoted at 76. The opposite side-cutting edge 77 of the blade may also be made generally concave in shape to follow the general shape of the opposite side surface 62 of the gear teeth. Such a tool may be used to simultaneously rough and finish. In cutting a gear with such a tool, the tool may start from the position 68₃ and be fed either in the direction of its axis 70 or with a swinging feed about the gear apex until it reaches full depth position 68₁. The depth feed may be made without generating roll. Then the roll begins and the involute profile 63 is described from the inside out during this generating roll. It will be seen that the finishing portion 69 of the tool does not cut during the infeed which is in the direction of said finishing portion. It is saved for finish-cutting. The depthwise cut is taken by the tip 72 of the tool and the cutting edges 76 and 77. The cutter is therefore a combination roughing and finishing cutter, having portions 69 used for finishing only, and other portions 76 and 77 used for roughing only. With this cutter and method it is good practice to rough and finish one side in one operation.

One method of finishing the opposite sides 62 of the teeth of the gear 60 is illustrated in Fig. 4. Here a face-mill cutter 80 is employed that has blades 81 which have straight side-cutting edges 82 that are of zero pressure angle, that is, that are parallel to the axis of the cutter. These blades may be made of shallow depth and may have gashes which are of less depth than the height of the tooth profiles to be cut. The bottoms of these gashes are denoted at 83.

With a cutter of the type shown in Fig. 4, the tooth profile 62 is preferably generated from the outside inwardly. Initial positions of the cutter and of the tooth profile are denoted at 81₁ and 62₁, respectively. In the generating operation, the work is rotated on its axis at a uniform velocity and a relative movement of translation is produced between the cutter and blank at a uniform velocity in the direction of the tangent 84 to the base surface 64 of the blank. In this movement, the point 86 in the cutting edge 82 of the tool describes the tooth profile 62. The dotted line 87 denotes the path of movement of the

cutting point 86 during withdrawal and return to cutting position.

Fig. 5 illustrates one method of roughing and finishing both sides of a tooth space in succession with a single tool according to another embodiment of the present invention. Here a gear 88 is to be cut that has involute tooth profiles 92 and 93.

Unlike the cutter of Fig. 4, the cutter 95 used in the method of Fig. 5 has both inside and outside cutting edges. The inside and outside cutting edges may be provided on each blade or on alternate blades. In the illustrated embodiment, the cutter is shown as having opposite side-cutting edges which for a portion of their height are of zero pressure angle as denoted at 96 and 97. The remaining portions of the cutting edges are of positive pressure angle as denoted at 104 and 102.

For roughing and finishing a tooth space which has opposite sides 92 and 93 of true involute profile, the cutter is first fed into depth and then the generating roll is begun. In the generating movement, the work is rotated on its axis at a uniform velocity and a relative translatory movement is produced between the tool and blank also at a uniform velocity in the direction of the tangent 98 to the base circle 99 of the blank. During this generating movement, the points 100 and 101 in opposite side cutting edges of the tool move along the tangent 98 and describe the involute tooth profiles 92 and 93.

On bevel gears, the roll along tangent 98 is a turning motion on an axis 110 which is perpendicular to the plane containing said tangent and containing the gear apex 111 (Figs. 6 and 7). The axis 110 passes through the apex 111 and the axis 105 of the cutter is parallel to the axis 110. The tip cutting edges 103 of the cutter project below the base line 98 of the gear blank as a rule as shown in Fig. 5. They project the same amount beyond the apex 111, as shown in Fig. 6, so that the root cone 112 of the blank has its apex at 113. 114 denotes the axis of the blank.

95, 95₁, 95₂, 95₃, 95₄, and 95₅ denote different positions of the cutter during the generating operation. The roughing cut from the solid is taken at first by the top cutting edges 103 of the cutter, but after the cutter has reached position 95₂, the roughing is also done by the inclined side-edges 102 and 104. It is never done, though, by the straight finish cutting edges 96 and 97. Up to position 95₃, the roughing cuts are taken by the tip cutting edge 103 and side cutting edges 102 and 104 while finishing is done by the point 101 in the right hand side cutting edge 97.

After one side 92 of the tooth space is finished, that is, after arriving at the position 95₃, the cutter is set-over relative to the gear blank, that is, it is automatically moved to a slightly different radial and angular position. Thus, its axis may be moved from a position such as denoted at 105 in Fig. 7 to the position 105'. The result is that the tip 103 of the cutter will thereafter cut along a path 106' instead of the path 106. It is as if the cutter had been slightly turned on an axis parallel to its own and passing through the small end of the tooth space being cut while the roll goes on. Inasmuch as the set-over is performed with the tool at full cutting depth and while cutting, the two set-over components should be timed with each other. This may be accomplished by hydraulic timing on known types of spiral bevel gear generators. In Fig. 5, 95₄ de-

notes a position of the tool where the set-over has been completed. The roll then continues to position 95₅. During this part of the roll, the point 100 in the side-cutting edge 96 will complete the finished tooth profile 93. The tool is then withdrawn from engagement with the blank and brought back to starting position and the blank is indexed.

When the opposite side-cutting edges are arranged on alternate blades, the finishing cuts may be taken by the points 100 and 101 under comparatively light cutting load. If desired, a "Triplex" type cutter may be employed having separate bottom-cutting and side-cutting blades so that the blades which take the finishing cuts may be relieved of practically all except finish cutting.

Modification of the roll may be employed for producing a desired amount of profile mismatch between mating gears and, if desired, for rounding off the tooth tops. This rounding off of the tooth tops is illustrated in Fig. 5. It could be done very accurately with the straight finishing profile 97 of the tool. This would lengthen the roll considerably, however. So the rounding off is preferably produced, as shown, with the rounded point of the tool by varying the ratio of roll slightly at both ends of the roll. Thus, at the beginning of the roll, the ratio of roll is so varied that the tool assumes the position 95₁ instead of the position shown in dotted lines at 95'. The latter position is the position which the tool would have were a true involute profile to be produced on the tooth surface for the full height of the tooth surface. In the position 95₁, the tool makes contact with the tooth profile 92 in the point 107, causing the rounding off of the profile 92 at its top. Likewise, at the end of the roll, the ratio of roll is again slightly varied, causing the side-cutting edge 96 to make contact at the point 108 and round off the profile 93 at its top.

With the method illustrated in Figs. 5, 6, and 7, it is possible to cut gears of zero or low spiral angle from the solid in a fast and accurate operation. The other methods described with relation to Figs. 3 and 4 are not confined to gears of low spiral angle. They can be applied also to gears of high spiral angle provided that the base circle is not inside the root circle. This condition is ordinarily present in mitre gears and gears of low reduction, but may require special tooth design on gears of large reduction in order to be achieved. The process of finishing from the solid as described with reference to Fig. 5 is also applicable to varying-leverage gears having wholly convex tooth profiles, if the feed movement employed is a swinging movement about the cone apex. Even without the swinging feed, it can be used provided that a spherical cutter of low pressure angle is employed such as is illustrated in Fig. 17. In this case, however, the motions for the two sides are unsymmetrical. When the swinging feed is used, the motions for the two sides are symmetrical so that computation of one side will do for both sides, and the same cams may be employed for all cone distances and cutter diameters for a given gear combination. The cutter also is a simple tool.

Although for finishing involute profiles, the work must be turned at a uniform rate for uniform roll movement of the cutter, considerable time may be saved without sacrifice of accuracy by speeding up the roll when finishing sharply curved portions of the tooth profiles. Thus the

work may be turned at a rate depending on the curvature at the point being finished, the rate increasing with increasing curvature. This does not affect the timing of the generating roll inasmuch as the cutter carrier or cradle may be sped up or slowed down simultaneously with the acceleration or deceleration of the work rotation.

This procedure may also be employed in the cutting of gears for transmitting non-uniform motion, where it has special advantages. According to present practice, it takes about twice as long to roll out the little round portion 43 at the top of the tooth profile 42 of the varying-leverage gear shown in Fig. 2 as it does to roll out the main portion of the profile. This is because the work must be turned through about twice the angle to produce the little round portion of the profile as to produce the main portion of the profile. The little round part 43 needs, though, only about half as many cuts as are now employed in order to get as good a finish as on the main portion of the profile. By speeding up the rate of roll when cutting the round 43, then, we may save about half the time heretofore spent on the round and cut down the total time of generation of the tooth about one-third. This change in rate of roll may be readily accomplished on small size generators where the roll is cam-operated and controlled, simply by employing a suitable generating cam.

An arrangement for varying the rate of roll in generators of the geared roll type is outlined diagrammatically in Fig. 3. The motor 120 drives the face-mill gear cutter 121 through a train of gearing which includes the bevel gears 122 and 123, the shaft 124, the change gears 125 and 126, the shaft 127, the bevel gears 128 and 129, and the shaft 130 on which the cutter 121 is mounted. On one end of the shaft 124 there is slidably mounted a friction gear 132. This friction gear 40 is keyed to the shaft 124 and is pressed by the spring 133 into engagement with the periphery of the cam 134. The cam 134 is fastened to a shaft 135 that is rotated once per cutting cycle, that is, once per tooth. The friction disc 132 engages another friction disc 137. This latter disc is secured to a shaft 138 which is perpendicular to and intersecting the shaft 124. The disc 137 is maintained in engagement with the disc 132 by pressure of a spring 139 which tends to shift the disc 137 and the shaft 138 toward the disc 132. The shaft 138 drives the generating mechanism of the machine. As will be obvious, the shaft 138 is turned at a faster or slower rate depending upon the axial position of the friction disc 132 and this, in turn, is controlled by the shape of the cam 134.

Where a swinging feed is employed in the cutting of bevel gears, the swinging feed is preferably controlled by a cam which turns continuously in the same direction once per cycle, that is, once per tooth. The modification in the ratio of roll may be obtained in known manner. To produce gears having concave and convex profile portions, such as shown in Fig. 1, it is also desirable to have the modification of the roll operated by a cam turning once per cycle. This arrangement simplifies the machine design. It is desirable, also, for generation of other types of varying motion gears.

Face-mill gear cutters which have cutting portions of zero pressure angle, that is, cutting portions extending in the direction of the axis of rotation of the cutter require a component of radial relief in order to have the required cutting clearance. Where the blades are radially relieved, 70

however, a slight change in cutter diameter occurs after sharpening. When individual inserted blades are used, they can readily be adjusted to the original cutter diameter after sharpening. In many cases, however, such individual radial adjustment is unnecessary. It is always desirable to provide spiral bevel or hypoid gears with a localization of lengthwise tooth bearing. I have found that for the life of the ordinary cutting tool, the change in radial position of the side-cutting edges may produce a change in localization of tooth bearing which is within acceptable tolerances and accordingly readjustment of the blades of the cutter after sharpening is not essential. The cutter may then simply be adjusted as a whole along the mean tooth normal so that the mean portion of the tooth is cut to the same radius at all times.

Figs. 9 and 10 show a face-mill gear cutter which may be employed for practicing the present invention. This cutter is of the segmental type and comprises a rotary head 145 and a plurality of cutting segments 146 which are secured to the head by bolts 147. Each segment is provided with a plurality of cutting teeth 148. The segments may be comparatively thin. They may be pressed to their curved shape from flat strips. They may be keyed to the cutter head by keys 150 which are secured to the cutter head by screws (not shown) and which engage in key slots 156. Cutting edges 150 are formed by gashes 151 which are of less depth than the depth of the teeth of the gear to be cut. The gashes are all alike and are equally spaced about the axis 162 of the cutter. The front faces of the blades may be sharpened with a side rake to provide keen cutting edges. The cutting blades 148 are relieved back of their cutting edges in axial and radial directions. The cutter shown in Figs. 9 and 10 has outside cutting blades only and the radial relief on a blade here extends inwardly in the direction denoted by the arrow 158 (Fig. 9).

Fig. 12 illustrates a modified form of segmental cutter in which the blades 160 have an outside curved finishing profile 161 which extends generally along the cutter axis and contains a point of zero inclination where the tangent to the profile is parallel to the cutter axis. The outside surface of the blade 160 is relieved in the direction of the arrow 163. The profile 161 is a circular arc and when the blade is new the center of the profile is at 162. A cutting profile such as may be obtained after repeated sharpenings is shown at 161'. Its center is at 162'.

Fig. 13 shows a segmental cutter having blades 170 with inside cutting edges 171 which are curved circular arcs centered at 172. These circular arcs have a point of zero inclination. The cutting profile is relieved inwardly in the direction of the arrow 178 and the position of the cutting edge after repeated sharpenings is denoted at 171'. Its center is at 172'.

Fig. 14 shows a cutter such as may be employed for cutting involute gears according to the method illustrated in Fig. 3. Here the cutter head is denoted at 186. The cutter is provided with inside cutting blades 181 and outside cutting blades 182. The blades are secured to the cutter head by screws 183. The inside cutting blade has an inside cutting edge 184 which is of straight profile parallel to the cutter axis, that is, of zero pressure angle, for a portion of its height and which is concave, as denoted at 185, for the remainder of its height. The portion 185 is used for roughing only, while the straight, zero-pressure angle

portion of the cutting edge is for finishing only. The outside cutting edges 186 of the blades are of concave profile shape and are used for roughing only.

Fig. 15 illustrates a cutter of slightly different structure from that shown in Fig. 14. The cutter has again alternate inside and outside blades denoted at 191 and 192, respectively. The outside blade 192 may be of the same structure as the blade 182, but the inside blade has an inside cutting edge 193 which is a circular arc that contains a point 194 whose tangent is parallel to the axis of the cutter, that is, which is of zero pressure angle.

In the cutters of both Figs. 14 and 15, the inside surfaces of the inside blades 181 and 191, respectively, have a combined axial and radial outward relief, being relieved in the directions of the arrows 187 and 197, respectively. The outside surfaces of the outside blades 182 and 192, however, on account of their larger inclination or pressure angle may be relieved in an axial direction only as indicated by arrows 188 and 198, respectively.

Fig. 16 shows a cutter such as may be employed for practicing the invention according to the embodiment illustrated in Fig. 5. This cutter has inside cutting blades 201 and outside cutting blades 202. The inside cutting blade 201 has a finish cutting edge 203 which extends for part of the height of the blade and which is of straight profile and parallel to the cutter axis, that is, which is of zero pressure angle. It also has an inclined side-cutting edge 204 which is of positive pressure angle and is intended for rough cutting only. In a similar manner, the outside cutting blade 202 has a straight side cutting edge 205 of zero pressure angle for finish-cutting and an inclined cutting edge 206 of positive pressure angle for rough-cutting. The finish-cutting edges 203 and 205 are about as long or longer than the active portions of the rough-cutting edges 204 and 206. The point width of the inclined cutting profiles 204 and 206, when prolonged to the top 207 of the blade, is less than half the point width of the profiles 203 and 205, and this point-width may, in fact, be zero or negative. The active sides of both the inside and outside blades have combined radial and axial relief, being relieved in the directions of the arrows 209 and 210, respectively.

Fig. 17 shows a spherical cutter which has a very low pressure angle on both sides. It has inside cutting blades 211 and outside cutting blades 212. The inside cutting edge 213 of the inside cutting blade 211 is a circular arc centered at 215 on the axis 216 of the cutter, while the outside cutting blade 212 has an outside edge 214 which is a circular arc centered at 218 on the axis 216 of the cutter. The distance between the sphere centers 215 and 218 is less than one third of the mean radius of the cutter, and the cutting edges of at least one side of the cutter contain a point 219 of zero pressure angle. Sometimes the two centers 215 and 218 may coincide. Both the inside and the outside active surfaces of the cutter have combined radial and axial relief, being relieved in the direction of the arrows 220 and 221, respectively. Cutters of this character may be used for cutting varying-leverage gears of convex profile in one operation from the solid without in-an-out feed by a process which is analogous to the one described with reference to Fig. 5.

While several different embodiments of the in-

vention have been described, it will be understood that the invention is capable of further modification, and this application is intended to cover any variations, uses, or adaptations of the invention, following, in general, the principles of the invention and including such departures from the present disclosure as come within known or customary practice in the gear art and as may be applied to the essential features hereinbefore set forth and as fall within the scope of the invention or the limits of the appended claims.

Having thus described my invention, what I claim is:

1. The method of cutting tooth surfaces of a tapered gear which comprises moving a cutting tool, that has a side-cutting edge of zero pressure angle at a point below its tip, across the face of a tapered gear blank so that its tip travels from one end of a tooth space to the other in a direction inclined to the pitch surface of the blank to cut a tooth surface tapering in depth from end to end, while simultaneously effecting a relative rolling movement between the tool and blank in a plane which is perpendicular to the cutting edge of the tool at said point to generate the tooth profiles with said point.

2. The method of cutting tooth surfaces of a tapered gear which comprises positioning a face-mill gear cutter, whose side-cutting edges are of zero pressure angle at at least one point in their heights, in engagement with a tapered gear blank so that a plane tangent to the base cone of the blank and perpendicular to the cutter axis also contains the pitch-cone apex of the blank, and rotating the cutter on its axis while producing a relative rolling movement at a uniform velocity between cutter and blank so that points of contact between the said zero pressure angle portions of the cutter and the blank remain in said tangent plane.

3. The method of cutting the tooth surfaces of a gear which comprises moving a cutting tool, that has a side-cutting edge of zero pressure angle at at least one point in its height, across the face of a gear blank while effecting a relative rolling movement at a varying ratio between the tool and blank and simultaneously producing a relative depthwise feed movement at a varying velocity between the tool and blank in time with said rolling movement.

4. The method of cutting tooth surfaces of a gear which comprises moving a cutting tool, that has a side-cutting edge of zero pressure angle at at least one point in its height, across the face of a gear blank while effecting a relative rolling movement at a varying ratio between the tool and blank alternately in opposite directions to effect forward and return generating movements, and producing a relative depthwise feed movement during both the forward and return rolls until the tooth profile has been cut for its full height, then withdrawing the tool from engagement with the blank, and indexing the blank.

5. The method of cutting tooth surfaces of a longitudinally curved tooth tapered gear which comprises positioning a face-mill gear cutter, whose blades have side-cutting edges of zero pressure angle at points below their tips, in engagement with a tapered gear blank so that the tip surface of the tool travels in a plane inclined to the pitch surface of the gear blank, and producing a relative rolling movement between the cutter and blank while effecting a relative angular feed movement between the cutter and blank about the apex of the blank until the tooth sur-

face has been cut to full depth, then withdrawing the cutter from engagement with the blank, and indexing the blank.

6. The method of cutting tooth surfaces of a gear blank which comprises employing a cutting tool, that has a side-cutting edge which is of zero pressure angle at a point below its tip and is of positive pressure angle below said point, and imparting a cutting motion to the tool while producing a relative rolling movement between the tool and blank in a plane perpendicular to the zero pressure angle portion of the tool in such timed relation that the positive pressure angle portion of the cutting edge rough-cuts a side tooth surface of the blank and the zero pressure angle portion finish-cuts the final profile shape of said tooth surface.

7. The method of cutting a gear which comprises cutting its opposite side tooth surfaces with opposite side-cutting edges, one of which is of straight profile and zero pressure angle for a part of its height and of positive pressure angle for the rest of its height and the other of which is of positive pressure angle for its full height, and imparting a cutting motion to the tool while producing a relative rolling movement between the tool and blank in such timed relation that the positive pressure angle cutting edges rough out opposite sides of a tooth space of a blank and the zero pressure angle portions finish-cut one side of the space during a generating cycle, and periodically indexing the blank.

8. The method of cutting a gear which comprises cutting its opposite side tooth surfaces with a tool that has a tip cutting edge and opposite side-cutting edges, each of the side-cutting edges being of straight profile and zero pressure angle for a part of its height and of positive pressure angle for the rest of its height, by imparting a cutting motion to the tool while producing a relative rolling movement between the tool and blank in such timed relation that the tip cutting edge of the tool and the positive pressure angle cutting edge at one side of the tool rough out one side of a tooth space of the blank and the corresponding zero pressure angle cutting edge finish-cuts that side of the tooth space during a part of the generating cycle, then shifting the tool relative to the blank and continuing the generating cycle to cause the positive pressure angle and zero pressure angle cutting edges at the other side of the tool to rough and finish-cut the opposite side of the tooth space, then withdrawing the tool from engagement with the blank and indexing the blank.

9. The method of cutting tooth surfaces of a gear blank which comprises employing a tool which has a cutting portion of zero pressure angle for part of its height and which is rounded at its tip, imparting a cutting motion to the tool, while effecting a relative rolling movement between the tool and blank to generate the tooth profiles; and varying the ratio of said rolling movement at one end of the roll so that the rounded part of the tool will generate a round on the tip of the gear tooth, and periodically indexing the blank.

10. The method of cutting tooth surfaces of a gear blank which comprises employing a face-mill gear cutter that has a plurality of circularly arranged cutting blades whose height is less than the height of the tooth surfaces to be cut and which has corresponding side-cutting edges that have a portion of zero pressure angle, positioning said tool in engagement with a gear blank so

that the tips of the blades travel from one end of a tooth space to the other in a plane inclined to the pitch surface of the blank, and effecting a relative rolling movement between the tool and blank in a plane perpendicular to the zero pressure angle portion of the blades in such timed relation that a point in the cutting edge of the tool below the tip of the tool generates the final tooth profile shape.

11. The method of cutting tooth surfaces of a gear which comprises employing a face-mill gear cutter that has a plurality of annularly arranged cutting blades whose height is less than the height of the tooth surfaces to be cut and which have corresponding side-cutting edges that at points below the tips of the blades are of zero pressure angle, positioning said tool in engagement with a gear blank so that the tip cutting edges of the tool travel from one end of a tooth space to the other in a plane inclined to the pitch surface of the blank, feeding the tool into the blank in the direction of the axis of the cutter, and producing a relative rolling movement between the cutter and blank in such timed relation with the feed motion that the finished tooth shape of the blank is generated by said points in the cutting edges of the tool below the tip of the tool, then withdrawing the tool from engagement with the blank and indexing the blank.

12. The method of cutting tooth surfaces of a gear which comprises employing a face-mill gear cutter that has a plurality of circularly arranged cutting blades which have convex side portions so curved that a tangent to a side portion of a blade at a given point therein is parallel to the axis of the cutter, rotating the cutter in engagement with a gear blank while producing a relative rolling movement at a varying ratio between cutter and blank and a relative depthwise feed movement at a varying rate between cutter and blank in such timed relation that the tangents to the cutting edges of the cutter at the specified points remain tangent to the tooth profile to be produced in all points of contact between the cutter and blank, and periodically indexing the blank.

13. The method of cutting tooth surfaces of a gear which comprises employing a face-mill gear cutter that has a plurality of circularly arranged cutting blades which have side-cutting edges that extend in the direction of the axis of the cutter, rotating said cutter in engagement with a gear blank while producing a relative rolling movement between the cutter and blank in a plane perpendicular to said cutting edges in such timed relation that the tooth profiles of the gear are generated by single points in corresponding side cutting edges of the cutter which lie below the tip of the cutter, and periodically indexing the blank.

14. The method of cutting tooth surfaces of a gear which comprises employing a face-mill gear cutter that has a plurality of circularly arranged cutting blades which have side-cutting edges that extend in a direction parallel to the axis of the cutter, positioning said cutter in engagement with a gear blank so that the cutter will cut tooth spaces in the blank tapering in depth from end to end, rotating the cutter in engagement with the blank, effecting alternate movements of feed and withdrawal between the cutter and blank about an axis passing through the apex of the blank, and producing a relative rolling movement between the cutter and blank in a plane perpendicular to said side-cutting edges in such

timed relation with the feed movement that single points in corresponding cutting edges of the cutter constitute the points of contact between the cutter and the tooth profile being generated throughout the whole of the generation of that profile, and indexing the blank during the periods of withdrawal.

15. The method of cutting the tooth surfaces of a gear which comprises effecting a relative rolling movement between a cutting tool and the gear blank alternately in opposite directions in such timed relation with a relative depthwise feed movement between the tool and blank that part of a tooth profile is generated during the forward generating movement and the remainder of the tooth profile is generated during the return generating movement.

16. The method of cutting the tooth surfaces of a gear which comprises effecting a relative rolling movement between a cutting tool and the gear blank alternately in opposite directions at a varying ratio in such timed relation with a relative depthwise feed movement between the tool and blank that part of a tooth profile is generated during the forward generating movement and the remainder of the tooth profile is generated during the return generating movement.

17. The method of cutting the tooth surfaces of a gear which comprises effecting a relative rolling movement between a cutting tool and the gear blank alternately in opposite directions in such timed relation with a relative depthwise feed movement at a varying rate between the tool and blank that part of a tooth profile is generated during the forward generating movement and the remainder of the tooth profile is generated during the return generating movement.

18. The method of cutting the tooth surfaces of a gear which comprises effecting a relative rolling movement between a cutting tool and the gear blank alternating in opposite directions at a varying ratio in such timed relation with a relative depthwise feed movement at a varying rate between the tool and blank that part of a tooth profile is generated during the forward generating movement and the remainder of the tooth profile is generated during the return generating movement.

19. The method of cutting the tooth surfaces of a gear which comprises effecting a relative rolling movement at a varying ratio between a cutting tool and a gear blank alternately in opposite directions while producing a relative depthwise feed movement between the tool and blank first outwardly and then inwardly at a varying rate, the inward feed movement occurring during the last part of the forward generating roll and during the first part of the return generating roll.

20. The method of cutting tooth surfaces of a gear which comprises employing a tool having a side-cutting edge of zero pressure angle at at least one point in its height and imparting a cutting movement to the tool while producing a relative rolling movement between the tool and blank in a direction perpendicular to the direction of said cutting edge at said point and simultaneously effecting a relative depthwise feed movement at a varying rate between the tool and blank in the direction of said cutting edge at said point.

21. The method of cutting a tooth surface of a gear which comprises employing a tool having a side-cutting edge of zero pressure angle at at least one point in its height and imparting a

7 cutting movement to the tool while producing a relative rolling movement at a varying ratio between the tool and blank in a direction perpendicular to the direction of said cutting edge at said point and simultaneously effecting a relative depthwise feed movement at a varying rate between the tool and blank in the direction of said cutting edge at said point.

22. The method of cutting tooth surfaces of a gear blank which comprises effecting a relative rolling movement at a varying ratio between a cutting tool and the gear blank to generate a tooth profile and accelerating the rate of the rolling movement at the end of the rolling movement to produce a round at the top of the tooth profile.

23. The method of cutting the tooth surfaces of a gear which comprises effecting a relative rolling movement at a varying ratio between a cutting tool and a gear blank while simultaneously effecting a relative depthwise feed movement at a varying rate between the tool and blank to generate a tooth profile, and accelerating the rate of the rolling movement at the end of the rolling movement to produce a round at the top of the tooth profile.

24. The method of cutting tooth surfaces of a gear which comprises moving a cutting tool, that has a side cutting edge of zero pressure angle at at least one point in its height, across the face of a gear blank while effecting a relative rolling movement at a varying ratio between the tool and blank, and producing a relative depthwise feed movement about the apex of the blank during the rolling movement until a side tooth surface of the blank has been cut for its full height, then withdrawing the tool from engagement with the blank, and indexing the blank.

25. The method of cutting tooth surfaces of a gear which comprises moving a cutting tool, that has a side cutting edge of zero pressure angle at at least one point in its height, across the face of a gear blank while effecting a relative rolling movement at a varying ratio between the tool and blank alternately in opposite directions to effect forward and return generating movements, and producing a relative depthwise feed movement about the apex of the blank first outwardly and then inwardly during the rolling movement until a side tooth surface of the blank has been cut for its full height, then withdrawing the tool from engagement with the blank, and indexing the blank.

26. The method of cutting side tooth surfaces of a tapered gear which comprises employing a face mill gear cutter, that has a cylindrical cutting surface whose axis coincides with the cutter axis, and rotating the cutter on its axis while effecting a relative rolling movement at a varying ratio between the cutter and a gear blank, and simultaneously producing a relative depthwise feed movement between the cutter and blank about the blank apex.

27. The method of cutting side tooth surfaces of a gear which comprises effecting a relative rolling movement at a varying ratio between a cutting tool and a gear blank while producing a relative depthwise feed movement between the tool and blank first outwardly and then inwardly.

28. The method of cutting side tooth surfaces of a tapered gear which comprises effecting a relative rolling movement at a varying ratio between a cutting tool and a gear blank while producing a relative depthwise feed movement

between the tool and blank first outwardly and then inwardly about the blank apex.

29. The method of cutting side tooth surfaces of a tapered gear which comprises employing a face mill gear cutter, that has side cutting edges which at at least one point in their height are of zero pressure angle, and rotating said cutter in engagement with a gear blank while effecting a relative rolling movement at a varying ratio between the cutter and blank, and simultaneously producing a relative depthwise feed movement between the cutter and blank first outwardly and then inwardly.

30. The method of cutting side tooth surfaces of a tapered gear which comprises employing a face mill gear cutter, that has side cutting edges which at at least one point in their height are of zero pressure angle, and rotating said cutter in engagement with a gear blank while effecting a relative rolling movement at a varying ratio between the cutter and blank, and simultaneously producing a relative depthwise feed movement about the blank apex between the cutter and blank first outwardly and then inwardly.

31. The method of cutting side tooth surfaces of a gear which comprises employing a cutting tool, that has a side cutting edge which has a finish cutting portion, that is of zero pressure angle adjacent its tip, and a rough cutting portion of positive pressure angle for the rest of its height, and imparting a cutting movement to the tool while effecting a relative rolling motion at a varying ratio between the tool and a gear blank in a plane perpendicular to the zero pressure angle portion of the tool.

32. The method of cutting side tooth surfaces of a gear which comprises employing a cutting tool that has a side cutting edge which has a finish cutting portion, that is of zero pressure angle adjacent its tip, and a rough cutting portion of positive pressure angle for the rest of its height, and imparting a cutting movement to the tool while effecting a relative rolling movement at a varying ratio between the tool and gear blank, and simultaneously effecting a relative depthwise feed movement between the tool and blank about the blank apex.

33. The method of cutting a side tooth surface of a gear which comprises employing a tool having a rounded tip cutting edge and imparting a cutting motion to the tool while effecting a relative rolling motion between the tool and the work, and varying the ratio of said rolling motion near the end of the roll to cause the tip cutting edge of the tool to round off the top of the gear tooth surface.

34. The method of cutting side tooth surfaces of a gear which comprises employing a tool having a side-cutting edge of zero pressure angle at a point below its tip, and imparting a cutting motion to said tool while effecting a relative rolling movement at a varying ratio between the tool and the gear blank in a direction perpendicular to the said cutting edge at said point, while producing a relative depthwise feed movement between the tool and blank first outwardly and then inwardly in the direction of said cutting edge at said point.

35. The method of cutting the tooth surfaces of a gear which comprises employing a cutting tool, which has a side-cutting edge that is of zero pressure angle at a point below its tip, and imparting a cutting movement to the tool while producing a relative rolling movement between the tool and the blank alternately in opposite directions in a plane perpendicular to the cutting edge of the tool at said point, and simultaneously effecting a relative depthwise feed movement between the tool and blank first outwardly and then inwardly at a varying ratio in the direction of the cutting edge of the tool at said point, the inward movement occurring during the last part of the forward generating roll and during the first part of the return generating roll.

36. The method of cutting side tooth surfaces of a gear whose side tooth surfaces are of concave profile shape for part of their height and of convex profile shape for the rest of their height, which comprises employing a face-mill gear cutter having circularly arranged cutting blades whose side-cutting edges are of zero pressure angle at points below their tips, and rotating said cutter in engagement with the blank while effecting a relative forward and return rolling motion between the cutter and blank in a direction perpendicular to the cutting edges of the tool at said points and at a varying ratio, and simultaneously producing a relative feed movement between the cutter and blank at a varying rate first outwardly and then inwardly in the direction of said cutting edges at said points, the forward part of the rolling movement being reversed when the said points in the cutting edges are cutting at the juncture of the concave and convex portions of a tooth profile, and the inward part of the feed movement occurring during the last part of the forward roll and during the first part of the return roll.
